DESIGN FOR A COMBINED WHEEL TRIM
RING AND HUB CAP OR SIMILAR ARTICLE

George Albert Lyon, Allenhurst, N. J.

Application September 25, 1943, Serial No. 111,207

Term of patent 14 years

(Cl. D14—30)

To all whom it may concern:

Be it known that I, George Albert Lyon, a citizen of the United States and a resident of the village of Allenhurst, in the county of Monmouth and State of New Jersey, have invented a new, original, and ornamental Design for a Combined Wheel Trim Ring and Hub Cap or Similar Article, of which the following is a specification, reference being had to the accompanying drawing, forming a part thereof.

On the drawing:

Figure 1 is a side elevation of the combined wheel trim ring and hub cap or similar article showing my new design.

Figure 2 is a profile view showing in outline a

diagrammatic sectional view of the structure shown in Figure 1.

Figure 3 is an enlarged fragmentary view of a portion of the design illustrating the contrast of the elements of the article.

In the several figures of the drawing the wheel trim ring A and hub cap B are shown in full lines, the dotted line disclosure being for illustrative purposes only.

I claim:

The ornamental design for a combined wheel trim ring and hub cap or similar article, as shown and described.

GEORGE ALBERT LYON.
